ICE BUCKET

Walter D. Teague, Jr., and Benjamin H. Stansbury, Jr.,
Alpine, N.J.

Application January 14, 1959, Serial No. 54,171

Term of patent 14 years

(Cl. D58—17)

FIG. 1.

FIG. 4.

Figure 3 is a side elevation view of the ice bucket, showing its rounded, tapered shape and the dark base.

Figure 1 is a perspective view of an ice bucket, showing our new design;

Figures 2 and 3 are front and side elevations, respectively, of the ice bucket; and

Figure 4 is a top plan view of the ice bucket.

We claim:

The ornamental design for an ice bucket, as shown.
